WRINGER

De Witt Clausen, Akron, Ohio

Application October 29, 1938, Serial No. 237,655

36 Claims.

(Cl. 68—249)

This invention relates generally to wringers for use in connection with household washing machines and the general aim of the invention is to provide a novel wringer having improved features of construction for facilitating its manufacture, operation and maintenance and for protecting the user against injury.

One of the major objects of the invention is to provide a wringer in which all stresses resulting from pressure on the rolls are confined within independent roll-controlling units so that the frame and housing of the wringer are relieved from such stresses.

Another object of the invention is to provide a new and improved wringer having a pair of free-floating rolls either of which is shiftable to effect an engagement or disengagement between the rolls and in which both rolls are spring-pressed to yield in opposite directions as articles pass therebetween.

Another object of the invention is to provide a new and improved wringer construction embodying a single lever operating mechanism for the complete control of the wringer.

Another object of the invention is to provide a new and improved wringer having inherent qualities of safety adapting it for extremely simple and foolproof operation.

Another object of the invention is to provide a wringer in which the safety release mechanism is part of the one-lever operating mechanism which is habitually used in the operation of the wringer, thereby rendering it the natural thing to use for releasing purposes in case of emergency.

It is a further object of the invention to provide a wringer embodying new and improved means for separating and releasing the pressure between the wringer rolls and simultaneously disconnecting the drive.

Another object of the invention is to provide a new and improved wringer construction in which a spring-pressed engagement is established between the rolls by bodily shifting one or the other of the rolls toward the coating roll, and in which the movement of one roll is utilized to establish a driving connection in one direction and optional movement of the other roll is utilized to drive the rolls in the opposite direction.

Another object of the invention is to provide a new and improved wringer which is of such simple, compact and light-weight construction that it may be manufactured at a low cost, the operating wringer mechanism comprising a small

number of parts and a relatively smaller number of differing parts.

Another object of the invention resides in the provision of a wringer embodying a relatively small frame supporting all of the operative structure of the wringer, and a light-weight detachable housing which serves merely to conceal and protect the internal mechanism.

A further object of the invention resides in the provision of a wringer of the above mentioned type in which all stresses due to wringer roll pressure are confined to tension members free floating in the wringer frame whereby the frame may be constructed of light weight to support the weight of the wringer mechanism only.

Another object of the invention is to provide a wringer having a one-lever control for selectively shifting one or the other of the rolls to establish a spring-pressed engagement with the 20 coating roll, for establishing a drive connection in one direction or the other depending upon which roll is shifted, and for releasing such spring-pressed engagement and driving connection to permit separation and free rotation of the 25 rolls, said last function being easily and quickly effected by the imposition of a relatively light force upon the lever conveniently disposed in a readily accessible position adjacent the area of feeding clothes to the wringer.

It is a further object of the invention to provide a wringer of this type adapted to be rotatably mounted for horizontal swinging movement upon a standard washing machine or other laundry equipment, and which embodies a new and improved safety indexing device for positively locking the wringer in one of a plurality of positions against swinging movement on its support when the driving gears are meshed and to prevent connection of the drive means when the 40 wringer is free to swing, said indexing mechanism being associated with the one-lever control and operated thereby.

It is a further object of the invention to provide a wringer of this type embodying an automatically tiltable drain spout for directing the flow of water from the rolls toward the feed side of the wringer regardless of the direction of rotation of the rolls.

It is a further object of the invention to provide a new and improved wringer embodying a release mechanism which is conveniently accessible from the side of the wringer from which clothes are fed thereto and which is operable from either side of the wringer in the same manner.

Other objects and advantages will become apparent in the following description and from the accompanying drawings in which:

Figure 1 is a small scale perspective view of a wringer embodying the features of the invention.

Fig. 1^a is a small scale side elevation of the wringer illustrating an alternative single lever control handle.

Fig. 2 is a side elevation showing the detachable housing in a raised position over the wringer structure.

Fig. 3 is a fragmentary perspective view of the operative structure of the wringer on an enlarged scale with the detachable cover removed.

Fig. 4 is a detail end elevational view in partial section showing the roll-shifting mechanism and bearing cages in roll-disengaged position.

Fig. 5 is a view similar to Fig. 4 showing the mechanism in one position for operative roll engagement.

Figs. 6, 7 and 8 are diagrammatic views illustrating the mechanism of Figs. 4 and 5 in roll-disengaged position, in roll-engaged position for rotation of the rolls in one direction, and in roll-engaged position for rotation of the rolls in the opposite direction, respectively.

Fig. 9 is a detail perspective view of a bearing cage.

Fig. 10 is a perspective view of the wringer frame.

Fig. 11 is a perspective view of an alternative wringer frame construction.

Fig. 12 is a detail view in horizontal section taken along line 12—12 of Fig. 13 showing a slightly modified form of roll shifting mechanism associated with the alternative frame construction of Fig. 11.

Fig. 13 is a detail view in vertical section taken along line 13—13 of Fig. 12.

Fig. 14 is a fragmentary view in end elevation of an alternative form of roll shifting mechanism.

Fig. 15 is a view in end elevation of an alternative roll tensioning mechanism.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

In prior wringers the stresses and strains caused by the operating pressure on the rolls have been borne by the wringer frame or parts thereof. Consequently, such frames have necessarily been made of strong and heavy construction to withstand the stresses. According to my invention, the operating mechanism of the wringer, including the rolls and the means for applying pressure thereto, is constructed as a unit within which all of the operating stresses and pressures due to roll tensioning are confined. This permits of the use of a supporting base or frame of light, compact construction, since it is required to support merely the weight of the operating mechanism. The construction also permits of the employment of a separate housing unit to enclose the pressure-applying means and to provide a clothes-guide and drain-board, which housing unit is quickly removable to expose the enclosed mechanism for inspection or repair. Since all stresses and strains due to the pressure between the rolls are

self-contained within said unit, the size and weight, and therefore the cost of manufacture of the housing and the supporting frame, are greatly reduced. The operation of assembling or disassembling the wringer as a whole is also simplified.

Referring to the drawings, which show an exemplary embodiment of the invention, the wringer comprises an elongated base or supporting frame 20 (Fig. 10) of light-weight construction, bolted, as at 21 (Fig. 2), to a swinging wringer carrying head 22. The frame comprises generally a sheet metal channel section having a partially concave web 24, two flanges 25, projecting at right angles to the web, and inturned flanges 26 paralleling the web and having end plates 27 and 27^a welded or otherwise secured to each end of the channel section. As indicated in Figs. 4, 5, and 10, the frame 20 is provided at each end with two sets of vertically aligned holes 28 in the web 24 and in the flanges 26, to receive sleeves 28^a for guiding two pairs of vertical tension bolts 29.

Four identical bearing cages 30, one of which is shown in Fig. 9, are vertically slideable on said bolts, two on each pair of bolts, one above the other. The upper cages support the journals 31 of an upper wringer roll 32 and the lower cages support the journals 33 of a cooperating lower roll 34. The bearing cages being identical, except that the position of the upper cages is inverted relative to that of the lower cages, a description of one will suffice for all. Referring to Figs. 3, 4, 5 and 9, each bearing cage comprises a tubular bearing 35 secured in a U-shaped inner yoke 36 having outwardly extending legs 37 perforated, as at 38, to receive the bolts 29 for sliding movement thereon. An outer yoke 39 has similarly perforated legs 40 for receiving the bolts. A pair of compression springs 41, interposed between the legs 37 and 40, tend to force the yokes apart and, as indicated, said springs may surround the bolts for compactness of structure. The yokes are tied together with the springs under suitable compression by a pair of headed pins 43 extending through and between the legs of the yokes preventing separation thereof but permitting relative approaching movement of the yokes to allow the bearings to yield against the compression of the springs upon roll engagement. The pins 43 are likewise disposed within the coiled springs 41 for compactness. Two yokes 44 beneath the frame are apertured to slide upon the pairs of bolts 29, being held in place by nuts 45 on said bolts.

Means is provided for controlling the positions of the bearing cages and the rolls therein, which means comprises cams associated with the bearing cages in such a manner that all stresses due to roll pressure are transmitted from one roll to the other through the tension bolts 29 to opposite sides of the cams, thereby confining the stresses to the roll-shifting and pressure-applying units and relieving the supporting frame therefrom. The extreme upper and lower yokes 39 and 44, respectively, and the bolts 29 constitute a sub-frame which is bodily shiftable as a unit relative to the main frame and the units are thus free-floating and self-contained and permit the rolls to shift independently of each other.

The control means comprises a cam shaft 46 journaled at 47 in the end plates 27 and 27^a of the frame, and having a pair of plate cams 48 fixed thereto near each end thereof between the lower bearing cages and the yokes 44.

As indicated in Fig. 4, the lower yokes 39 of the

lower bearing cages coat with and ride on the working surfaces of the cams for supporting the weight and controlling the movement of said lower roll and its bearing cages, the web 24 of the frame being apertured at 49 to permit such coaction. A pair of light-weight springs 50 are mounted between the upper and lower cages to normally urge the rolls apart under a relatively light pressure and to support the weight of the upper roll and its associated parts on the lower roll when the rolls are disengaged. In this position the bolts 29 are supported by their headed portions 51 on the outer yoke of the upper cages and the yokes 44 are supported thereby for similar coaction with the opposite working surface of the cam.

Each cam is provided with a peripheral working curve having a segment 52 substantially concentric with its axis of rotation, a segment 53 raised to provide the desired roll-shifting movement, and two diametrically opposed segments 54 and 55 slightly lowered to provide seats in which the yokes 39 and 44, respectively, normally rest when the rolls are disengaged. The cams are rotatable in either direction to shift the rolls into pressure engagement and, as indicated in Fig. 5, rotation of the cams in one direction raises the lower roll bearing cages, while the yokes 44 ride on the concentric segments of the cams, and, through the agency of the bolts, hold the upper roll-bearing cages against upward movement. Thus the cams, in effect, act as wedges between the lower bearing cages and the yoke 44 forcing the rolls into spring-pressed engagement. The pressure between the rolls is transmitted through the rolls, roll journals, bearings, the yokes 36, the springs 41, and the yokes 39 to the bolts directly from the upper roll and through the control cam and yoke 44 from the lower roll. It will be apparent that each cam is embraced by a pair of opposed cam engaging surfaces associated respectively with the individual roll-supporting units for the upper and lower rolls, so that, when the surfaces are spread apart by the cams, the rolls will be tensioned. The cam thus serves merely to carry the weight and control the roll movement and, upon engagement, is self-locking and receives a substantially equal and opposite compressive strain on its opposite faces.

The control cams may likewise be rotated in the other direction (counterclockwise, as viewed in Fig. 4) to draw the upper roll downwardly for engagement with the lower roll through the agency of the yokes 44, bolts and upper bearing cages while the lower roll bearing cages remain substantially stationary. A very small upward movement is imparted to the lower roll as the slightly raised segment 52 of the cam 48 comes into contact with the yoke 39. Thus either roll is bodily shiftable toward the cracting roll to effect an engagement in which both rolls are spring-pressed to yield in opposite directions. It is an important feature of the invention to utilize this optional movement of the rolls to establish a drive connection in one direction when one roll is shifted and to drive the rolls in the opposite direction when the other roll is shifted, whereby the direction of rotation of the rolls may be reversed for feeding clothes thereto from either side of the wringer.

The exemplary wringer herein disclosed being of the swinging type well known in the art, the drive mechanism 56 is, in part, of conventional form and, as shown in Fig. 2, embodies a power shaft 57, introduced through the rotatable

wringer carrying head 22. The head 22 comprises a metal casting apertured at 21, as mentioned heretofore, for the purpose of bolting the frame 20 thereto and the lower end of said head has an enlarged flanged base 58 and a depending sleeve portion 59. The head is rotatably seated on a stationary tubular post 60 having a cooperating flanged bearing portion 61 upon which the base 58 rests and into which the sleeve 59 extends. The power shaft is arranged to be connected with a suitable source of power, such as a drive shaft of a household washing machine, and extends vertically through the post 60, sleeve 59 and into the head 22, wherein it is journaled by means of a bearing 62 in the head. A horizontally disposed bevel gear 63 is fixed to the upper end of the power shaft, which gear is in constant mesh with a take-off bevel gear 64 fixed to a horizontal stub shaft 65 journaled in a bearing 66 of said wringer carrying head. The inner ends of the roll shafts 31 and 33 are extended somewhat beyond the limits of the bearing cages and have fixed on their ends pinions 67 and 68, respectively, adapted to mesh with a pinion 69 fixed on the shaft 65. As illustrated in Figs. 2, 6, 7 and 8, it will be seen that, upon shifting the lower roll into engagement with the upper roll, the pinion 68 will mesh with the pinion 69 to positively rotate the lower roll, which will normally rotate the upper roll by reason of the frictional tensioned engagement therebetween. Upon optional shifting of the upper roll the pinion 67 will mesh with the pinion 69 to drive the rolls in the opposite direction. In this manner the rolls are made to rotate in opposite directions even though each roll, when engaged with the driving pinion, always turns in the same direction. When clothes pass through the wringer the rolls are separated under pressure and each roll moves an equal amount up and down. As both rolls are equally spring-pressed, they merely float with the varying amount of the thickness of the material passing therethrough, thus eliminating the necessity of one roll taking all the movement which might tend to force the pinions out of engagement.

This form of drive connection results in a simple and compact unit, in that the necessity of employing reversing gears or a clutch mechanism is obviated. Both rolls may be positively driven, if desired. In either event the rolls are free to rotate after releasing.

The cams as illustrated are mounted beneath the rolls and bearing cages but it is to be understood that the same principle may be applied where the cam shaft is otherwise positioned, or where two cam shafts are employed as illustrated alternatively in Fig. 14. In such an arrangement the movement of the rolls is under the control of separate sets of cams 70 and 71, the sets being carried on separate cam shafts 72 and 73 respectively. In the event that such construction were employed, a control lever for each cam shaft would be provided and movement of each roll would be independently controlled by a separate control lever.

At the inner end of the cam shaft 46 a rigid extension 81 is detachably connected therewith, said extension having an oval-shaped collar portion 82 (Fig. 3) for circumjacently straddling the drive shaft 57. The free end of the extension 81 has a pair of ears 83 between which a control lever 80 is pivotally supported at 87.

The control lever extends arcuately up over the inner end of the wringer and is thus conveniently accessible for manipulation by the operator. Se-

lective manipulation of the lever from its roll disengaged position above the wringer (as seen in full outline in Fig. 1) to either side of the wringer adjacent the clothes-feeding area (as seen in dotted outline) will shift one roll or the other for establishing tensioned roll engagement and a driving connection, so as to cause rotation of the rolls in one direction or the other depending upon which way the lever is shifted. The direction of rotation of the driving gear 69 causes rotation of the roll with which it is meshed in such a direction that clothes may be fed to the wringer from the side to which the lever is shifted.

In this arrangement the lever is readily accessible to the operator within a few inches of the feed area for quickly and easily releasing the roll pressure and the drive in case of emergency and, in this connection, it will be seen that the length of the control lever is several times that of the maximum throw of the cams so that only a relative light force need be imposed thereon for releasing. Such releasing movement is further facilitated by the shape and location of the cams relative to their following parts. From their roll-engaged positions the cams need be moved only a small fraction of an inch to initiate the releasing movement after which they are automatically cammed the rest of the way out of engaged position by the following yokes (see Figs. 4, 5, 6, 7, and 8). The control lever thus serves in addition as an efficient safety release mechanism and, being habitually used in the operation of the wringer, thereby becomes the natural thing to use for releasing purposes in emergencies. A modified form of control lever 85, as shown in Fig. 1^a, extends the entire length of the wringer and is connected with the cam shaft at both ends.

The control lever has two other functions. The cam shaft which it operates has fixed thereto, by straps 86 (Fig. 2), a drain spout 87, which is positively and automatically tilted when the shaft is rotated, for directing the flow of water from the rolls toward the feed side of the wringer regardless of the direction of rotation of the rolls. The shaft is offset for compactness of structure, as indicated at 88 in Figs. 2 and 3, and the drain spout is secured on the offset portion thereof beneath the frame. The web 24 of the frame is dished or hollowed out, as indicated at 89, for catching the drain water from the rolls and directing it to an aperture 90 in the center of the frame which opens to the drain spout.

The control lever serves also as an actuating control in conjunction with a safety indexing device 91 for the dual purpose of locking the wringer in one of a plurality of positions against swinging movement on its support when the gears are meshed, and for preventing the establishment of a driving connection between the power source and the rolls when the wringer is free to swing. In the peripheral face of the flanged portion 61 of the post 60, a plurality of notches or indentations 92 are formed to receive the latching end 93 of a detent lever 94 pivoted on the base of the wringer head at 95. A coiled spring 96 seated in the wringer head normally urges the latching end 93 of the lever into the notches 92 from which said end may be moved by actuating the lever against the force of the spring 96. The wringer carrying head thus may be swung to any desired position and locked in said position, through the medium of the detent 94 with its latching end 93 in the notches 92.

The control lever 80 is pivoted in such a manner that it may swing about the axis of the cam

shaft and also may swing lengthwise thereof. Beneath the pivotal point 97, an integral finger portion 98 is formed on the lever 80 for cooperation with and actuation of the detent 94. As the lever 80 is swung away from the wringer (as indicated in dotted outline in Fig. 2), in a vertical plane, the finger 98 actuates the detent to release its latching end from the notches 92 and permit swinging of the wringer. When the lever 80 is thus rotated the finger 98 integral therewith enters a notch 99 in the carrying head to prevent rotation of the cam shaft by the lever and, when the lever can be actuated for rotation of the cam shaft, the finger 98 will not cooperate with the detent to move it out of latched position. Thus when the lever is actuated to establish a driving connection there is no possibility of releasing the wringer for swinging movement and when the wringer is free to swing the lever cannot be actuated to establish a driving connection.

It will be apparent that the complete operation of the wringer is under the control of a single lever which establishes a driving connection with the rolls in either direction, applies and releases the spring pressure, stops the rolls from turning, separates the rolls to a fixed distance, operates the drain spout and indexes the wringer to any particular operating position.

Means affording protection and concealment of the wringer mechanism are provided in the form of an independent removable housing 100 which serves in addition as a clothes-guide and drain-board. As seen to advantage in Figs. 1, 1^a and 2, the housing has sections 101 covering the end portions of the wringer mechanism and laterally projecting side portions 102 serving to guide the clothes to and from the rolls and direct the flow of drain water therefrom. The upper roll remains completely exposed to view on both sides of the wringer for clear and unobstructed observation of the material passing through the rolls, whereby any wrapping of clothes around the rolls may be detected immediately. The housing is provided with inwardly projecting hooks 103 for cooperation with eyes 104 fixed to the frame 20 for holding the housing in position. The housing thus is easily removable by a simple lift to expose the wringer mechanism for inspection or repair.

In this connection it will be apparent that the entire wringer is characterized by a simplicity of construction, being built of sub-assemblies, such that its assembly and dismantling is extremely simple. After lifting the housing 100 all that is required for the removal of the rolls and their associated bearing cages and tension means is to unscrew the four nuts 45 beneath the frame and lift out the sub-assemblies. The frame may be easily removed from the carrying head by releasing the bolts 21 therebetween and withdrawing the cam shaft 46 from the extension 81.

Referring to Figs. 11, 12 and 13, an alternative form of wringer frame 112 is illustrated wherein the bearing cages are guided in their sliding movement by side stiles 110 and 111 integral with the supporting frame. As shown in Figs. 12 and 13, the yokes 36^a, 39^a, and 44^a have flanged end edges 114 which are received within channel sections 115 for guiding the cages. In this modified construction, the weight of the roll supporting unit, comprising the cages 30^a, the tension bolts 29, and the yoke 44^a, is supported on the cam 48 and cam shaft 46 which in turn is journaled, as at 47, in the end walls of the frame, and the bolts 29 serve only the purpose of tension mem-

bers to receive the stress due to wringer roll pressure.

A modified form of roll tensioning means is illustrated in Fig. 15, wherein only a single set of compression springs 117 are employed for tensioning the rolls upon engagement. A lower roll bearing support 118 is directly actuated through rotation of the cam 48 in a clockwise direction to shift the lower roll 34 upwardly for engagement with the upper roll 32. Such shifting movement compresses the springs 117 through the agency of an upper roll bearing support 119, bolts 29 and a lower yoke 120 acting on the springs. Rotation of the cam in a counter-clockwise direction shifts the upper roll downwardly for pressure engagement with the lower roll through the agency of the yoke 44, springs 117, yoke 120, bolts 29, and yoke 119. It will be apparent that the roll shifting and tensioning operations of this modified form involve substantially the identical principles as described heretofore in connection with Figs. 4 and 5, the upper roll bearing cage springs being transplanted to a position beneath the frame and the lower roll bearing cage springs being eliminated. The latter springs might be included, if desired, to permit yielding of the lower roll as articles pass between the rolls. However, it is to be understood that the principles of the present invention might well be applied to a wringer construction having no roll tensioning springs at all and wherein the rolls are of the proper composition to impart sufficient resiliency to the pressure engagement to permit yielding thereof as articles pass therebetween.

I claim as my invention:

1. A wringer having, in combination, a pair of rolls each mounted for independent movement toward and away from the other, means for applying spring pressure to urge the rolls into operative engagement, and means operative selectively to shift either of the rolls into engagement with the other in its substantially unshifted position.

2. A wringer comprising, in combination, a pair of wringer rolls, means for mounting each roll for relative movement toward and away from the other, spring means acting on one roll to urge that roll toward the other, and means operable for selectively moving either roll into operative engagement with the other.

3. A wringer comprising, in combination, a pair of cooperating rolls, bearings in which said rolls are journaled, spring means acting on the bearings of each roll to urge each roll toward the other, means for mounting the bearings and spring means associated with the respective rolls for relative shifting movement thereof as units toward and away from each other, and control means operative selectively to shift either of the units toward the other while holding that other substantially stationary to establish a yieldable spring pressed engagement between the rolls.

4. A wringer comprising, in combination, a frame, a pair of cooperating wringer rolls, a pair of free floating bearing cages in support of each roll and slidably in said frame, each of said rolls and its associated bearing cages being shiftable toward and away from the other, and resilient means within said cages and slidable therewith, said means being tensioned upon operative engagement of the rolls to permit both rolls to yield as articles pass therebetween.

5. A wringer comprising, in combination, a pair of wringer rolls; supporting bearings in which

said rolls are journaled; bearing cages in support of said bearings; and means for mounting each roll and its associated bearing cages for sliding movement toward and away from the other; each of said cages including a yoke in support of a bearing, a spring abutment spaced from said yoke, and spring means acting between said abutment and said yoke, whereby to maintain a yieldable operative pressure between the rolls upon engagement.

6. A wringer comprising, in combination, a pair of cooperating wringer rolls; a frame; a pair of bearing cages supporting each roll and vertically slidably in each end of said frame; each of said cages including a spring abutment, a wringer roll bearing and spring means interposed between said abutment and said bearing to urge each roll toward the roll cooperating therewith; and a single manipulable means operative selectively to shift the abutments associated with one or the other of the rolls to effect operative pressure between the rolls.

7. A wringer comprising, in combination, a main supporting frame; a pair of coacting rolls; two roll-supporting units located at opposite ends of said rolls and supported by said frame; each of said units including a sub-frame which is guided for shifting movement relative to said main frame, bearings for said rolls, and spring means for exerting pressure on the rolls, the bearings for one of said rolls being shiftable with the sub-frames as a whole and the bearings for the other roll having a relative slidable relationship to the respective sub-frames, and means for selectively shifting the latter bearings or the sub-frames and the opposing bearings to move said rolls into and out of operative relation.

8. A wringer comprising, in combination, a support, a pair of coacting rolls, two pairs of shiftable bearings for the respective rolls, means for mounting said bearings on said support, means for exerting pressure on said bearings, and a one lever operating means coacting with opposed parts of said mounting means and serving selectively to move either pair of said bearings toward or away from the other for shifting said rolls into and out of operative relation.

9. A wringer comprising, in combination, a pair of coacting rolls, two pairs of shiftable bearings in which said rolls are respectively journaled, an actuating device, means associated with said bearings and operated by said actuating device for shifting either pair of said bearings toward the other to bring said rolls into engagement when said actuating device is operated, and means for exerting spring pressure upon said rolls when they are brought into such engagement.

10. A wringer comprising, in combination, a pair of coacting rolls, two pairs of shiftable bearing units in which said rolls are respectively journaled, at least one pair of said units being elastic to permit yielding of their roll relative to the opposing roll, means for guiding said units in their relative shifting movements, and means acting upon both pairs of said units for selectively shifting one or the other pair to move the rolls therein toward or away from each other.

11. A wringer comprising, in combination, a pair of coacting rolls, a pair of upper and a pair of lower bearing cages in which said rolls are journaled, each of said cages having spring means for exerting pressure on said rolls when in engagement, spring means acting to urge the respective upper and lower cages apart, tension

means connecting the respective upper and lower cages and acting to limit such separating movement of said cages, and means for shifting either the upper or lower pair of cages toward or away from the other pair to move the rolls into and out of spring pressed engagement.

12. A wringer comprising, in combination, a pair of coacting rolls, two pairs of opposed bearing devices in which said rolls are respectively journaled, means for shifting either pair of said bearing devices toward the other to bring said rolls into coacting engagement, means operative when the rolls are in engagement for exerting spring pressure thereon, a frame supporting the weight of said rolls and said bearing devices, and means connecting said bearing devices and serving to receive the thrust of said pressure-exerting means independently of said supporting frame.

13. A wringer comprising, in combination, a supporting frame; a pair of coacting rolls; means carried by said frame for supporting said rolls to permit shifting of either roll toward the other; said means comprising two units located at the ends of the rolls, each of said units embodying opposed bearings in which the rolls are journaled, spring means for exerting pressure on said bearings when said rolls are in engagement, and means for shifting either of the opposed bearings toward the other to effect such spring-pressed engagement, each unit being constructed to receive within itself the thrust of said spring-pressure exerting means without transmitting such thrust to said supporting frame.

14. A wringer comprising, in combination, a pair of rolls, two pairs of bearings in which said rolls are respectively journaled, each pair being independently shiftable toward and away from the other, means operable selectively to shift either pair of bearings to carry either roll into pressure engagement with the other, and means associated with the bearings and with the operating means and serving to receive the thrust resulting from the pressure on the rolls.

15. A wringer comprising, in combination, a pair of coacting rolls, two pairs of bearing units in which said rolls are respectively journaled, each pair of said units being shiftable relative to the other to bring said rolls into engagement, each of said units being elastic to exert pressure on the rolls upon engagement, resilient means acting to urge the respective pairs of units apart, operating means for shifting either pair of units toward the other pair to move the rolls into pressure engagement, and tension means associated with the bearing units and with the operating means and acting to limit the separating movement of the units and serving to receive the thrust created by the pressure between the rolls.

16. A wringer comprising, in combination, a frame, a pair of coacting rolls, two pairs of opposed bearing cages in which said rolls are respectively journaled, said cages being shiftable in said frame, and being elastic to exert pressure on the rolls upon engagement, resilient means acting to urge the respective pairs of cages apart, an actuating device, means associated with said cages and with said actuating device and acting to limit the separation of said pairs of cages, said means being operable by said actuating device for shifting either pair of said cages toward the other to bring said rolls into pressure engagement when said actuating device is operated, said means serving when said device is

thus actuated to receive the roll pressure independently of said frame.

17. A wringer comprising, in combination, a pair of cooperating wringer rolls each mounted for movement toward and away from the other, means for selectively shifting either roll, and driving means engageable by movement of the shifted roll to drive the rolls in one direction or the other depending upon which roll is shifted.

18. A wringer comprising, in combination, a pair of cooperating wringer rolls, each mounted for movement perpendicularly toward and away from the axis of the other, means for selectively moving either roll into pressure engagement with the other, and driving means engageable by movement of the shifted roll to drive the rolls in one direction or the other depending upon which roll is shifted.

19. A wringer comprising, in combination, a pair of coacting rolls, an individual driven element for each roll, each of said elements being operable independently of the other element, a driving element common to said individual driven elements, means for selectively shifting one or the other of the individual driven elements into direct engagement with the common driving element to effect the feed of clothes in one direction or the other depending upon which individual driven element is shifted.

20. A wringer comprising, in combination, a support, a pair of coacting rolls, bearing means carried by said support for mounting both of said rolls for bodily shifting movement, a common driving pinion element, driven pinions for rotating the respective rolls, and means for shifting said bearing means to carry either one of said driven pinions into driving engagement with said common driving pinion.

21. A wringer comprising, in combination, a support, a pair of coacting rolls journaled for bodily shifting movement relative to said support, a common driving element, a driven element on each of said rolls, each of said elements being operable independently of the other element, and means for shifting one or the other of said rolls to carry said driven element thereon into direct driving engagement with said common driving element.

22. A wringer comprising, in combination, a pair of cooperating wringer rolls either of which is shiftable toward the other to effect a pressure engagement between the rolls, a driving element on each roll, a driving element having a fixed position and engageable by the driving element on the shifted roll to drive the rolls in one direction or the other depending which roll is shifted, and manipulable means for selectively shifting either roll to effect engagement or disengagement of the driving elements.

23. A wringer comprising, in combination, a pair of cooperating wringer rolls, roll supporting means shiftable mounted for engaging movement of each roll toward the other, means for applying pressure to the rolls upon engagement thereof, and control means for shifting either roll for engagement with the other while holding that other substantially stationary, said control means including a rotatable cam having an operative connection with both roll supporting means such that said cam receives equal and opposite roll pressures from the rolls upon engagement.

24. A wringer comprising, in combination, a frame, a pair of cooperating wringer rolls, individual roll-supporting means shiftable mounted in said frame for relative engaging and dis-

engaging movement of the rolls toward and away from each other, control means for selectively shifting either roll-supporting means to move its roll into engagement with the other roll, said control means including a cam-engaging surface for one roll-supporting means spaced from the axis of the roll supported thereby, a second cam-engaging surface for the other roll-supporting means disposed in a plane intermediate the first mentioned cam-engaging surface and the axis of the roll supported by said one roll-supporting means, and a cam interposed between said surfaces and in continuous engagement therewith, said cam being formed so that selective rotation thereof will shift one or the other of the rolls into pressure engagement with its cooperating roll while holding the cooperating roll substantially stationary.

25. A wringer comprising, in combination, a frame, a pair of coacting rolls, individual roll-supporting means movably mounted in said frame to permit shifting of said rolls relatively toward and away from each other, an actuator therefor, said means each having portions embracing a rigid part of said actuator in such relation that when said portions are spread by said actuator the rolls will be drawn together, and means for operating said actuator.

26. A wringer comprising, in combination, a pair of coacting rolls, individual roll supports for each roll, said supports being slidable to permit relative movement of the rolls toward and away from each other, resilient means tending to urge the rolls apart, cam engaging surfaces on each of said supports, said surfaces being disposed in overlapping spaced relation to each other so that the separation tendency of the rolls tends to close the space between said surfaces, and a cam interposed between said surfaces to limit the amount of roll separation, said cam being rotatable to further separate said surfaces for drawing the rolls together.

27. A wringer comprising, in combination, a frame, a pair of coacting rolls, individual roll supporting units slidable in said frame to permit each roll to shift relative to the other, resilient means tending to separate the units, each of said units having a cam engaging surface overlapping and disposed in spaced relation to each other, and a cam interposed between said surfaces and selectively rotatable in said frame to further separate the surfaces for shifting either roll into pressure engagement with the other, said cam having a working curve such that when rotated to a roll engaged position it is in stable equilibrium and only a slight rotation back initiates releasing movement after which the separating tendency of the units automatically completes the releasing movement.

28. A wringer comprising, in combination, a pair of coacting rolls mounted for shifting movement toward and away from each other for engagement and disengagement, resilient means acting between the respective rolls and tending at all times to separate the rolls, means limiting the separating movement, and control means for shifting the rolls into pressure engagement and releasable to permit limited separation of the rolls.

29. A wringer comprising, in combination, a pair of cooperating rolls each mounted for shifting movement into and out of engagement with the other; roll tensioning means operable upon engagement of the rolls; and manually operable cam means for shifting the rolls, said cam means

having one position of adjustment in which the rolls are disengaged, a second position in which one roll is shifted for engagement with the other roll and a third position in which said other roll is shifted to engage said one roll.

5 30. A wringer comprising, in combination, a vertical standard, a wringer frame rotatably supported for swinging movement on said standard, a pair of coacting rolls journaled in said frame 10 for shifting movement of either roll for engagement with the other, driving means engageable by movement of the shifted roll to drive the rolls in one direction or the other depending upon which roll is shifted, resilient means effective to 15 tension the rolls upon engagement thereof, a single lever control means for shifting either roll into and out of yieldable pressure engagement with the other, a tiltable drain spout having a connection with said control means and 20 automatically tiltable thereby to one side of the wringer or the other depending upon the direction of rotation of the rolls, latching means for indexing the wringer frame in one of a plurality of positions on said standard and means associated with said lever and operated thereby for 25 releasing the latching means only when the rolls are disengaged and for preventing engagement of the rolls by the lever when it is actuated for releasing the latching means, whereby the complete 30 operation of the wringer is controlled by a single lever.

31. A laundry wringer comprising, in combination, a pair of wringer rolls, either roll being shiftable to effect an operative pressure engagement with the other, driving means engageable by movement of the shifted roll to drive the rolls in one direction or the other depending upon which roll is shifted, a single lever control 35 means for selectively shifting either roll into engagement with the other, said means having a normal roll-disengaged position in which the lever assumes a position above the wringer rolls, said means having two roll-engaged positions, one in which one roll is shifted to rotate the 40 rolls in one direction, clothes being fed thereto by movement of the shifted roll to drive the rolls in the opposite direction, clothes being fed thereto from one side of the wringer, and a second position in which the other roll is shifted to rotate the rolls in the opposite direction, clothes being fed thereto from the other side of the wringer, 45 said roll-engaged positions being effected by shifting the lever selectively to the side of the wringer from which it is desired to feed the clothes and to a point adjacent the feeding area 50 convenient of access to the operator for releasing in case of emergency.

55. 32. A wringer comprising, in combination, a pair of coacting rolls, a frame in which said rolls are shiftably mounted for engaging movement of either roll toward the other, driving 60 means engageable by movement of the shifted roll to drive the rolls in one direction or the other depending upon which roll is shifted, control means for shifting either roll to effect a pressure engagement with the other, and a drain 65 spout having an operative connection with said control means and automatically tiltable thereby to direct the drain water to one side or the other of the wringer depending upon the direction of rotation of the rolls.

70 33. A wringer comprising, in combination, a frame, a pair of coacting rolls journaled for shifting movement in said frame toward and away from each other, means for selectively shifting either of said rolls for pressure engagement with the other, a tiltable drain spout be-

neath said rolls, and a connection between said drain spout and said shifting means for automatically inclining said spout toward one side of the wringer or the other depending upon which roll is shifted.

34. A wringer comprising, in combination, a frame, a pair of coacting rolls journaled for rotation in said frame, driving means for said rolls, means including a rotatable shaft extending longitudinally of and beneath said rolls for selectively controlling the direction of rotation of said rolls, and a drain spout fixed on said shaft and automatically tilttable thereby for directing the flow of drain water from the rolls toward the side of the wringer from which clothes are fed thereto.

35. A wringer comprising, in combination, a supporting frame, a pair of cooperating wringer rolls, a pair of supporting bearings for each roll, spring means acting on said bearings to urge each roll toward the other, and rigid tension

means free floating in said frame and mounted to receive at opposite ends thereof the reacting force of the spring means associated with the respective rolls, whereby said tension means is subjected to equal and opposite stresses imparted thereto by the roll pressure through said spring means, thereby eliminating all stresses due to wringer roll pressure from said supporting frame.

36. A wringer comprising, in combination, a pair of cooperating wringer rolls each mounted for movement toward and away from the other, means for selectively shifting either roll into operative pressure engagement with the other, a driving pinion having its axis disposed intermediate the axes of said rolls, and driven pinions on each of said rolls, said driven pinions being engageable selectively with said driving pinion for driving the rolls in one direction or the other depending upon which roll is shifted.

DE WITT CLAUSEN.

CERTIFICATE OF CORRECTION.

Patent No. 2,327,998.

August 31, 1943.

DE WITT CLAUSEN.

It is hereby certified that error appears in the printed specification of the above numbered patent requiring correction as follows: Page 6, second column, line 34, claim 20, after "pinion" strike out --element--; and that the said Letters Patent should be read with this correction therein that the same may conform to the record of the case in the Patent Office.

Signed and sealed this 9th day of November, A. D. 1943.

(Seal)

Henry Van Arsdale,
Acting Commissioner of Patents.
